(57) **CLAIM**

The ornamental design for computer lock, shown and described.

DESCRIPTION

FIG. 1 is a front side perspective view showing our new design for computer lock;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top view thereof;

FIG. 7 is a bottom view thereof.

FIG. 8 is a reduced scale perspective view thereof, shown in its environmental use; and,

FIG. 9 is a perspective view thereof, with bolt regulating buttons shown in an extended position.

The broken lines in FIGS. 8 and 9 are for illustrative purpose only and form no part of the claimed design.
